(57) **CLAIM**

The ornamental design for a multi-compartment resealable storage bag, as shown and described.

DESCRIPTION

FIG. 1 is a top, front perspective view of a first embodiment of the multi-compartment resealable storage bag, showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a top, front perspective view of a second embodiment of the multi-compartment resealable storage bag, showing my new design;

FIG. 8 is a rear elevational view thereof;

FIG. 9 is a top plan view thereof;

FIG. 10 is a bottom plan view thereof;

FIG. 11 is a left side elevational view thereof;

FIG. 12 is a right side elevational view thereof;

FIG. 13 is a top, front perspective view of a third embodiment of the multi-compartment resealable storage bag, showing my new design;

FIG. 14 is a rear elevational view thereof;

FIG. 15 is a top plan view thereof;

FIG. 16 is a bottom plan view thereof;

FIG. 17 is a left side elevational view thereof;

FIG. 18 is a right side elevational view thereof;

FIG. 19 is a top, front perspective view of a fourth embodiment of the multi-compartment resealable storage bag, showing my new design;

FIG. 20 is a rear elevational view thereof;

FIG. 21 is a top plan view thereof;

FIG. 22 is a bottom plan view thereof;

FIG. 23 is a left side elevational view thereof;

FIG. 24 is a right side elevational view thereof;

FIG. 25 is a top, front perspective view of a fifth embodiment of the multi-compartment resealable storage bag, showing my new design;

(Continued)

FIG. 26 is a rear elevational view thereof;
 FIG. 27 is a top plan view thereof;
 FIG. 28 is a bottom plan view thereof;
 FIG. 29 is a left side elevational view thereof;
 FIG. 30 is a right side elevational view thereof;
 FIG. 31 is a top, front perspective view of a sixth embodiment of the multi-compartment resealable storage bag, showing my new design;
 FIG. 32 is a rear elevational view thereof;
 FIG. 33 is a top plan view thereof;
 FIG. 34 is a bottom plan view thereof;
 FIG. 35 is a left side elevational view thereof;
 FIG. 36 is a right side elevational view thereof;
 FIG. 37 is a top, front perspective view of a seventh embodiment of the multi-compartment resealable storage bag, showing my new design;
 FIG. 38 is a rear elevational view thereof;
 FIG. 39 is a top plan view thereof;
 FIG. 40 is a bottom plan view thereof;
 FIG. 41 is a left side elevational view thereof;
 FIG. 42 is a right side elevational view thereof;
 FIG. 43 is a top, front perspective view of an eighth embodiment of the multi-compartment resealable storage bag, showing my new design;
 FIG. 44 is a rear elevational view thereof;
 FIG. 45 is a top plan view thereof;
 FIG. 46 is a bottom plan view thereof;
 FIG. 47 is a left side elevational view thereof; and,
 FIG. 48 is a right side elevational view thereof.
 The broken line showings of portions of the multi-compartment resealable storage bag represent perforations and form part of the claimed design.
